UNITED STATES PATENT OFFICE

ROBERT C. SMALLEY, OF ARLINGTON, NEW JERSEY, ASSIGNOR TO CLAUDE NEON LIGHTS, INC., OF NEW YORK, N. Y., A CORPORATION OF NEW YORK

METHOD OF PRODUCING VACUUM-TUBE-LAMP ENVELOPES OF SPECIAL DESIGN

Application filed June 2, 1926. Serial No. 113,306.

This invention relates to vacuum tube lights such for example as the well-known neon lights in which a column of more or less rarefied gas, as for example neon, contained in a transparent envelope, is caused to glow by the passage of an electric current therethrough and more particularly my invention contemplates an improved method for producing vacuum tube lights of special design such as words written in a characteristic way, and the like.

It is an object of this invention to provide a convenient and simple method for making special tubes which will eliminate the delay, inconvenience and inaccuracies of the old method.

It is a further object of this invention to provide a method for making special tubes whereby the handling during the shaping and forming operations is decreased and simplified and the accuracy increased, and production of such lamps thereby expedited.

It is still a further object of this invention to provide a method for making lamp envelopes of the class described which will furnish permanent working records or patterns of the lamps produced.

Still other objects of my invention will be apparent from the specification.

The features of novelty which I believe to be characteristic of my invention are pointed out with particularity in the appended claims. My invention itself however, both as to its underlying principles and as to its practical embodiments will best be understood by reference to the specification and accompanying drawings in which:

Figure 1 illustrates the first stage of my method after the proposed design has been laid out on paper;

Figures 2 and 3 are respectively plan and elevation views of the lay-out in the second stage of the method;

Figure 4 is a plan view of the tubing after it has been formed or worked to the desired design; and

Figure 5 is a perspective view of the completed lamp or light mounted on a base ready for operation.

Lamps of the class described are usually

used in advertising signs and are frequently formed in the shape of words such as trademarks, characteristic design and the like. In the past it has been customary to make such lamps by first laying out the desired design in actual size upon paper. This paper was then placed upon a work bench and the glass-blower proceeded to take sections of tubing and work them as near as possible to the desired design. He usually provided himself with a number of spacing blocks which might be placed upon the paper to support the tube in process of being worked out of contact with the paper to avoid burning the same and upon which the tubing rested while being worked. In forming the tubing he would bend the tube as far as possible to correspond with the design while sighting down at the design. Since the tubing was spaced from the paper carrying the design, parallax caused inaccuracies in the bending and other disadvantages were encountered.

In certain words and designs it is necessary that the tubing be bent back upon itself as for example, in the small letter "d"; if this is to be joined to a following letter the tubing must be bent upon itself over practically the entire distance of the vertical line of the "d". In such cases it is preferable to bend the tubing back upon itself and behind itself. In the formation of such letters according to the old process it was necessary for the glass blower therefore to bend or splice tubing under a piece of tubing already in position which was necessarily difficult and awkward and resulted in delays and therefore hampered production of the lamps.

Moreover the bulbs containing the electrode had to be spliced on and when the tubing was worked as above described the bulbs had to be spliced on between the tubing already in position, and the table; in other words, in the space afforded by the spacing blocks. For these reasons and for others the formation of glass tubing into the desired design was a tedious and uncertain process, and the product frequently failed to conform to the design as well as might be desired.

According to my invention I eliminate the necessity for the spacing blocks, the neces-

sity for working the tubing under and behind tubing already in position, and the guess work in shaping the tubing to the desired design by laying out the design to actual size and in reverse on non-combustible and heat-insulating material such as asbestos paper or cloth and by carrying on the forming and bending operations on the glass tubing while it is lying directly upon and in contact with the asbestos paper.

Since the tubing lies upon the paper and the design traced thereon is of the same size as the tubing, the accuracy of working the tubing is greatly increased, as the tubing may be heated and shaped to lie precisely upon the design. Moreover, reverse bends are made by bending the tubing down above tubing already in position instead of bending it underneath tubing in position as was the case in the old method and furthermore, in attaching the bulbs containing the electrodes, the ends of the tubing are simply bent up and the bulbs spliced on to project upwardly instead of downwardly. After the tube has been formed to the desired shape, the asbestos sheet carrying the design may be filed away and as will be readily understood, forms a permanent fire-proof record or pattern of the tube which may be utilized later if additional tubes of the same pattern are desired.

Referring now more particularly to Figure 1, suppose it is desired to produce a vacuum tube light showing the word "Ace" written as shown in Figure 1. The artist or designer will lay out the word in the style and size desired upon an ordinary sheet of paper 1. The outlines of the design may then be traced by perforations as for example by utilizing a perforating wheel 2 which is run over the lines of the design leaving a line of perforations 3.

The sheet 1 carrying the design will then be placed face downward and secured in position upon a suitable sheet of asbestos paper or cloth 4. Suitable marking material such as lamp black may then be dusted or distributed over the sheet 1 and more particularly upon the lines of perforations forming little piles 5. The lamp black may then be rubbed through the perforations by the fingers or a suitable tool, after which the paper may be removed and the design will be outlined as a mirror image of the artist's layout, in black upon the asbestos sheet.

This sheet may then be placed upon the glass blower's work bench and the tubing formed as already described by taking ordinary tubing 10, making the necessary bends 11 and splicing where desirable. The glass blower may for example in making the letter "A" as shown in Figure 4 make the bend 11 at the apex of the "A", then an additional bend to form the cross bar of the "A".

At this point, where it is necessary to bend the tubing back upon itself, or to make

a reverse bend, instead of finding it necessary to bend under the cross bar already in position as would have been the case in the old method, he may now make a bend in such manner that the reversely bent portion 12 lies above the cross bar of the "A". In a similar manner in the reverse bend of the "c", portion 12 which according to the old method would have been made under the already formed portion is now made on top and finally in splicing on the bulbs 14 containing the electrodes 15 a simple upward bend is made on the tubing and the bulbs spliced thereto. The lamp envelope is now completed and is ready for exhausting, filling and sealing. After completion, the lamp may be suitably supported upon the base 16 in such manner that the bulbs 14 are concealed behind the base 16 and the lamp tubing passes through suitable holes 17 therein. If now suitable voltage be applied between the electrodes the illuminated word "Ace" will appear in the same style as laid out by the artist or designer.

While I have shown and described certain preferred embodiments of my invention it will be understood that modifications and changes may be made without departing from the spirit and scope of my invention as will be readily understood by those skilled in the art.

What I claim is:

1. The method of producing a vacuum tube lamp envelope of predetermined design which comprises laying out the design in reverse on non-combustible material and working the envelope tubing in contact therewith to fit said design.

2. The method of producing a luminous tube envelope of predetermined design which comprises laying out the design in reverse on non-combustible and heat-insulating material, and working the envelope tubing in contact therewith to fit said design.

3. The method of producing a luminous tube envelope of predetermined design which comprises laying out the design upon relatively thin fibrous material, transferring the design in reverse to heat resistant material, and working the envelope tubing in contact therewith to fit said design.

4. The method of producing a luminous tube envelope of predetermined design which comprises laying out the design upon paper, transferring the design in reverse to non-combustible and heat-insulating material and working the envelope tubing in contact therewith to fit said design.

5. The method of producing a luminous tube envelope of predetermined design which comprises laying out the design upon relatively thin fibrous material, transferring the design in reverse to non-combustible material and working the envelope tubing in contact with said material to fit said design.

6. The method of producing a luminous

tube envelope of predetermined design which comprises laying out the design upon paper, transferring the design in reverse to heat resistant material and working the envelope tubing in contact with said material to fit said design.

7. The method of producing a luminous tube envelope of predetermined design which comprises laying out the design upon relatively thin fibrous material, perforating said fibrous material along the lines of the design, placing the fibrous material carrying the design upon heat resistant material, distributing marking material over said fibrous material to pass through said perforations and to transfer the design in reverse to said heat resistant material, and working the envelope tubing in contact therewith to fit said design.

8. The method of producing a luminous tube envelope of predetermined design which comprises laying out the design upon paper, tracing the lines of the design with a perforator, placing the perforated paper face downward in contact with a sheet of asbestos paper, distributing marking material upon the paper to pass through said perforations and mark the design in reverse on said asbestos, and working the envelope tubing in contact with said asbestos paper to fit the design outlined thereon.

9. The method of producing a vacuum tube envelope of predetermined design having certain portions substantially in one plane and other portions substantially at right angles to said plane which comprises laying out the design in reverse on non-combustible material, working the envelope to fit the design and bending the said other portions in a direction away from the non-combustible material.

10. The method of producing a vacuum tube envelope of predetermined design which comprises laying out the design in reverse on a sheet of asbestos and working the envelope in contact therewith to fit said design.

11. The method of producing a vacuum tube lamp envelope of predetermined design which comprises laying out the design upon paper, perforating the paper along the lines of the design, placing the paper design in reverse upon a sheet of asbestos, distributing lamp black over the paper to pass through the perforations and to transfer the design in reverse to the asbestos, and working the envelope tubing in contact therewith to fit said design.

12. The method of making a sign of luminescent tubing, comprising the steps of laying out the design of the tubing as a positive, transferring the design in reverse to a heat resistant surface, and bending the tubing to conform to the design in reverse, whereby the normally hidden return bends of the tubing are on the side toward the operator.

13. The method of producing luminescent

tubing of predetermined design which comprises laying out the design in reverse on a surface and working the tubing in contact therewith to fit the said design.

14. The method of producing a luminescent tube sign, which comprises laying out the design in reverse on a surface, shaping the tube in contact therewith to fit said design, and mounting the shaped tubing on a base.

15. The method of making a sign of luminescent tubing comprising the steps of laying out the design in reverse, and bending the tubing to conform to the design in reverse, whereby the normally hidden return bends of the tubing are on the side toward the operator.

In testimony whereof, I have hereunto set my hand this 21 day of May, 1926.

ROBERT C. SMALLEY.
